UNITED STATES PATENT OFFICE

MATTHEW LANG, OF AKRON, OHIO

ROLLER SKATE

Application filed May 2, 1929. Serial No. 359,741.

My invention relates to roller skates, and my object in general is to provide a strong and speedy skate embodying only two wheels, preferably rubber-tired wheels to cushion shocks and prevent noise and skidding. The skate is made in two sections having interlapping extensions adapted to permit the skate to be lengthened or shortened, and each extension is arranged to interlock with 10 the opposite section to distribute the load and strain. Single wheels being employed for each skate section, provision is also made to take up the side thrust and strains on the sections and the wheels. The wheels are also 15 provided with ball bearings, and the skate is constructed to permit these parts to be readily removed and replaced, all as hereinafter shown and described and more particularly pointed out in the claim.

20 In the accompanying drawings, Fig. 1 is a top view of a skate embodying my improvements, and Fig. 2 is a side elevation thereof. Fig. 3 is a sectional view longitudinally through the skate. Figs. 4 and 5 are vertical sections on lines 4—4 and 5—5 respectively, of Fig. 3. Fig. 6 is a bottom view of the skate. Fig. 7 depicts a modification.

The skate comprises a front section A, and a rear section B, having flat extensions or 30 tongues *a* and *b*, respectively, placed in overlapping relation on the longitudinal medial line of the skate. Section A includes a flat rest or pad 2 for the sole of a shoe, and tongue *a* is depressed and offset in respect to this pad 35 so that the top face 3 of the tongue lies in a lower horizontal plane than the bottom surface 4 of the pad. The tongue is widened at its base to the same width as top portion 2, and a slot or recess 5 is provided in this 40 widened part at the bend or offset 6, thus permitting the overlapping extension *b* of rear section B to pass through the opening beneath pad 2. A cross-piece or keeper 7 extends transversely between two depending 45 legs 8—8 on section A, and this keeper is spaced apart from the bottom of pad 2 to interlock with and hold the extremity 9 of tongue *b* against vertical and lateral movement, thereby re-enforcing and supporting 50 the bent or offset portion in tongue *a* where

weakened by opening 5 therein. Tongue *b* is formed with a slot 10 to receive a pair of clamping bolts 11, and these bolts pass through tongue *a* to receive clamping nuts 12 for fastening the sections rigidly together, except when extensible adjustments are made. The bottom tongue *a* extends rearwardly beneath the heel supporting top 14 of section B and a cross-piece or keeper 15 is also provided between the legs 16—16 of rear section B to confine and support tongue *a*. Cross piece 15 also serves as a brace for the legs 16—16 which are integral parts of top 14 and of substantial thickness to support the load and resist lateral strains inasmuch as 60 only a single wheel W is confined centrally of the skate between the legs. The lower extremities of legs 16—16 have axially aligned openings for a removable spindle or axle 17, and cotter pins 18 or equivalent locking 70 means extend vertically through openings in the side bosses 19 of the legs and the opposite ends of said shaft. A similar mounting is provided for the front wheel W between legs 8—8, and like parts relating 75 thereto and the wheels are herein designated by the same characters or numerals.

Thus, each spindle or axle 17 is provided with a key 20 and two flanged ball bearing cones 21 confined between the two legs, and each wheel W comprises a flanged metal body having a hub 22 formed with ball races containing anti-friction balls 23. Dust caps 24 are secured over the hubs, and the flanged rim 25 of the wheel carries a rubber tire 26 which is held removably in place thereon by a flanged screw ring 27 attached to one side of the wheel body. The wheel axle may be readily removed from its supporting legs upon withdrawing the cotter pins, and the 80 complete wheel assembly may then be handled independently for replacements and repairs. When the parts are assembled the ball bearings take up the side thrust on the 85 wheels.

To permit the skate to be fastened to the foot, rear section B is formed with a semi-circular flange 28 to receive the heel of a shoe, and a buckle strap 29 is secured to the flange at side opening 30 therein. The front 100

section A which seats the sole of the shoe is provided with a channeled flange or lugs 31 at one border edge to receive and grip one edge of the sole of a shoe, and an adjustable 5 clamp 32 is slidably affixed by a screw 33 to the opposite edge of section A to grip the sole and press the shoe laterally against the channeled flange 31. A nut 34 is pocketed with- in a side depression 35 in clamping member 10 32, and the screw 33 passes through the nut and is formed with a round extension 35' having rotatable bearing within the upper part of the legs, see Fig. 4. As shown, the 15 legs are molded integral with the sole and heel sections, and preferably each section is molded from aluminum or an alloy of light weight, and the legs and the foot and heel plate portions of each section made relatively thick and heavy to provide a skate of sub- 20 stantial rigidity and strength to support the user in a state of balance or equilibrium on two wheels arranged one behind the other on the longitudinal median line of the skate.

Each skate section may be stamped, forged 25 or otherwise formed in lieu of molding it as described.

In Fig. 7 I show an end view of a skate C constructed as herein described, excepting that the wheels W' are mounted at a slight 30 angle of inclination relatively to the shoe clamping part of the skate. In other words the axle for each wheel W' is inclined horizontally to permit the wheel to revolve in an inclined plane centrally beneath the top of 35 the skate, and this arrangement is especially desirable in a two wheel skate to permit the skater to more readily maintain his balance and to control his movements. As shown, the center of the wheel is located on the ver- 40 tical median line of the skate.

What I claim, is:

A roller skate comprising front and rear foot supporting members, a pair of wheel supporting legs depending from each mem- 45 ber, a keeper rigidly secured to the legs of each member and spaced from the member, a tongue extending rearwardly from the front member and between the rear member and keeper, and a tongue extending forward- 50 ly from the rear member and between the front member and keeper, one of said tongues being offset and provided with a slot through which the other tongue extends.

In testimony whereof I affix my signature.

55 MATTHEW LANG.
